(57) **CLAIM**

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon, showing my new design; and,

FIG. 2 is a front view of a display screen or portion thereof with icon of FIG. 1, in which a mobile terminal in broken line is provided to illustrate an example environment.

The broken lines showing a display screen or portion thereof form no part of the claimed design.

**1 Claim, 2 Drawing Sheets
(2 of 2 Drawing Sheet(s) Filed in Color)**

FIG. 1

FIG. 2
